VALVE TESTING APPARATUS

Reed J. Caughey, Schenectady, N. Y., assignor to
 General Electric Company, a corporation of
 New York

Application December 1, 1938, Serial No. 243,399

6 Claims. (Cl. 73—51)

This invention relates to valve controlling apparatus and more specifically to apparatus for testing valves in relatively high pressure fluid conduit systems.

5 In conduit systems for supplying high pressure elastic fluid to consuming apparatus such as turbines, a stop valve is usually provided for interrupting the flow of elastic fluid in the system in accordance with a predetermined abnormal condition of operation of the consuming apparatus. 10 In many installations such emergency valves are not operated during extended periods of time and during such periods of inoperation sedimentary formations, corrosion, or other abnormalities may 15 cause the valve to stick or render it incapable of instantaneous operation. Means are usually arranged in the valve control system whereby such emergency valves may be tested from time to time to ascertain their operating condition. Such 20 testing is usually done by moving the valve to a slightly closed position sufficient to satisfy the inspector that the valve is in working condition, the valve being immediately thereafter restored to the full open position. In certain installations, 25 because of the relatively high fluid pressure acting upon the upper surface of the valve disk, the valve, if moved slightly too far in testing, may become unbalanced to such an extent that it will be suddenly moved to the fully closed position 30 against the force of the operating mechanism. Before the valve can be restored to its open position, it is necessary to close the control valves to the after connected apparatus so that the back 35 pressure may be built up by the opening of the stop valve pilot to the point at which the main valve disk may be opened by its operating motor. Such unintentional closing of the stop valve is 40 undesirable since the continuity of operation of the after-connected apparatus is thereby disrupted.

It is an object of this invention to provide a new and improved arrangement for testing the operability of a valve in service.

It is a further object of this invention to provide 45 a new and improved arrangement for testing stop valves in relatively high pressure elastic fluid systems whereby unintentional closing of the valve is precluded.

In accordance with the illustrated embodiment 50 of the invention, means are provided in conjunction with the valve operating motor whereby during the testing operation the motor will be allowed to move only to a predetermined valve closing position and may thereafter be restored 55 to the previous fully opened condition without

danger of the valve being accidentally moved to the fully closed position by virtue of faulty manipulation of the testing auxiliaries.

For a consideration of what I believe to be novel and my invention, attention is directed to the following description and the claims appended thereto taken in connection with the accompanying drawing.

In the drawing, Fig. 1 is a diagrammatic sketch illustrating one embodiment of my invention, 10 while Fig. 2 is a detailed view showing the pilot valve of Fig. 1 in a second position of adjustment.

Referring to the drawing, 10 is a valve arranged in an elastic fluid system of relatively high pressure, the direction of flow therethrough 15 being represented by the arrow 11. The valve disk 12 may be of any well-known form suitable for use with high fluid pressures. The valve is adapted to be operated to the opened position by means of a fluid motor 13, the piston 14 slidably 20 arranged in cylinder 15 being operatively connected to the valve stem 16. The valve is normally biased to the closed position by means of a spring 17 shown in this instance as being arranged within the motor cylinder above the 25 piston 14. Operating fluid under pressure may be supplied from any suitable source through the conduit 18, the supply thereof to the motor being usually controlled by a control or, pilot valve 19 and by a trip valve 20 arranged in series as regards the direction of fluid flow through the connecting conduits 21 and 22. The pivot valve 19 includes a cylinder 23 having spaced apart heads 24 and 25 arranged on the stem 26. The stem is adapted to be operated manually, or otherwise, 35 by a first operating lever 27 pivoted at 28 on the bracket 29. The lower end of the lever 27 is connected by a link 30 to the upper end of the stem 26. The stem is biased upwardly by means of the spring 31 arranged between the upper end 40 of the cylinder and the collar 32 secured onto the stem, the spring being normally held under compression by the toggle arrangement of the lever 27 and link 30 as shown in full line in Fig. 1. In this position, communication is established 45 through the pilot valve between the conduits 18 and 21. When the pilot valve operating lever 27 is rotated in a clockwise direction to a position as shown in dotted line, the toggle is broken and the stem will be moved upwardly under the force of 50 spring 31. As the valve head 25 moves past the port of the connection 21, fluid will be drained from the cylinder of the motor 13 through the open end 33 of the pilot valve cylinder resulting in the closing of the valve 10. The trip valve 20 55

may be of any suitable type, such as the dia-
grammatic arrangement shown, which comprises
a cylinder 35 having spaced apart heads 36 and 37
provided on the stem 38 slidably arranged there-
in. The stem is biased to the right by the suit-
ably arranged spring 39 retained in the position
shown by means of the latch 40, which in turn
is adapted to be released in response to any
abnormal condition of the steam consuming appa-
ratus such as excess speed of a turbine. For ex-
ample, a governor 41 embedded in the turbine
shaft 42 may be arranged for tripping the latch
arm 43 upon the occurrence of a predetermined
abnormal speed condition. Due to the action of
the spring 39, the valve heads will then be moved
to the right shutting off the supply of operating
fluid from the conduit 21 and permitting the fluid
within the cylinder of the motor 13 to drain
through the conduit 22 and the open end 44 of
the tripping valve.

The arrangement and the operation thereof
thus far described is well-known in the prior art.
According to my invention, I provide a connec-
tion 45 communicating with the cylinder of the
motor 13, the inlet port thereof being adapted
to be closed by the piston 14 at a position corre-
sponding to approximately the one-fourth closed
position of the valve 10. The other end of the
connection 45 communicates with the pilot valve
19, the outlet port therein being controlled by
the valve head 46 fixed upon the stem 26. In
the normal position, as shown, the valve head
46 closes the port of the connection 45. A second
operating lever 47 is pivoted as at 48 upon the
bracket 49, one end of the lever extending above
the collar 32 fixed on the stem 26. For testing
the operating condition of the main valve 10,
the lever 47 is rotated about its pivot in the
clockwise direction as shown best in Fig. 2 forcing
the pilot valve stem downwardly. It will be noted
that the link 30 is provided with a longitudinal
slot 50 for accommodating the downward move-
ment of the pilot valve stem. The downward
movement of the stem may be limited by means
of a stop 51 provided on the bracket 49 and adapt-
ed to be engaged by the lever 47. With reference
to Fig. 2 it will be noted that the limited down-
ward movement of the pilot valve stem slightly
uncovers the port of the connection 45 so that
fluid is allowed to drain from the cylinder of the
motor 13 and escape from the pilot valve through
the clearance hole 52 around the stem. Down-
ward movement of the pilot valve stem for un-
covering the port 45 does not affect the communi-
cation between the operating fluid supply conduit
18 and the conduit 21 so that operating fluid is
continuously supplied to the motor 13 during the
testing operation. Downward movement of the
piston 14 and consequently the closing movement
of the valve 10 is limited by the location of the
port in the side wall of the cylinder 15 which
port is closed upon a predetermined downward
movement of the piston 14. When the test is
completed, that is, the operating condition of the
stop valve ascertained, the testing lever is re-
leased whereupon the pilot valve port of the
connection 45 will again be closed by the action
of the spring 31. Fluid pressure within the motor
13 will again build up and restore the main valve
to its previous fully opened position.

It is obvious that the exact location of the
port of the connection 45 in the cylinder 15 may
be varied as desired relative to the valve opened
position of the piston 14. It is a general prac-
tice, however, to provide operating motors for

stop valves of such a size as are capable only
of opening the valve disk against a maximum
pressure drop thereacross of approximately 15%.
It is necessary under such conditions, therefore,
to so position the port that while testing the
stop valve it will not be moved to such a closed
position that the pressure drop thereacross be-
comes greater than this value. With a pressure
drop greater than this value occurring there-
across, the valve will be forced to the closed posi-
tion against the opposing force of the operating
motor fluid pressure. Roughly, a proper position
of the port corresponds to approximately the
one-fourth closed position of the valve though
it is obvious that the most desirable position
therefore may be readily calculated by one skilled
in the art taking into consideration the various
factors involved.

Having described the principle of operation of
my invention together with the apparatus which
I now consider to represent the best embodiment
thereof, I desire to have it understood that the
apparatus shown is only illustrative and that
the invention may be carried out by other means.

What I claim as new and desire to secure by 25
Letters Patent of the United States is:

1. The combination comprising a main valve
adapted to be arranged in a relatively high pres-
sure fluid system, a fluid pressure operated motor
for normally maintaining said valve in the 30
opened position, means biasing said valve to the
closed position, a source of operating fluid con-
nected to said motor, a conduit extending from
said motor, a pilot valve in said conduit for drain-
ing operating fluid from said motor to cause a 35
closing movement of said main valve, the port
of said conduit in said motor being so arranged
as to be closed by said motor upon a predeter-
mined partly closing movement of said main
valve. 40

2. The combination comprising a main valve, a
fluid pressure motor connected to said valve for
normally maintaining said valve in the opened
position, spring means normally biasing said
valve to the closed position, a conduit for con-
ducting operating fluid to said motor, a control
valve arranged in said conduit, means for op-
erating said control valve to shut off the supply
of operating fluid to said motor and allowing
the escape of fluid therefrom, and means for al-
lowing the escape of fluid from said motor only
until said motor is moved an amount corre-
sponding to a predetermined partly closed posi-
tion of the main valve. 45

3. In combination, a stop valve arranged in a 55
relatively high pressure fluid conduit, a motor
having a cylinder and a piston slidably arranged
in said cylinder, said piston being operably con-
nected to said stop valve, means biasing said pis-
ton to the valve closed position, a source of oper-
ating fluid, a conduit connecting said source to
said motor, a pilot valve arranged in said conduit
for controlling the flow of operating fluid to and
from said motor, a second conduit communicat-
ing with said motor having an opening in the 60
cylinder thereof and so positioned therein that
it is closed upon a predetermined valve closing
movement by said piston, means provided on
said pilot valve for controlling the drainage of
operating fluid from said motor cylinder through
said second conduit, and means for operating
said pilot valve whereby fluid may be drained
from said motor to permit only a predetermined
valve closing movement thereof while communi- 70
75

cation is maintained between the source of operating fluid and said motor.

4. Operating apparatus for a stop valve arranged in a relatively high pressure fluid conduit, said apparatus comprising a fluid pressure motor having a cylinder and a piston, means for connecting said piston to said stop valve, means for biasing said motor to the inoperative position, a source of operating fluid for said motor, 10 a conduit for supplying operating fluid from said source to said motor, a pilot valve arranged in said conduit for controlling the flow of operating fluid to and from said motor, a second conduit extending between said motor and said pilot 15 valve, the opening of said second conduit in said motor being so located as to be closed by said piston upon a predetermined movement thereof corresponding to a partly closed movement of said stop valve, said pilot valve being so arranged that 20 operating fluid may be drained from said motor through said second conduit while communication is maintained between the source of operating fluid and said motor.

5. A valve testing arrangement comprising a valve, a fluid pressure operated servo motor having a piston connected to said valve for normally maintaining said valve in the opened position

sition, a source of pressure fluid, conduit means including a control valve for conducting pressure fluid from said source to said motor, a second conduit extending between said motor and said control valve, means for operating said control valve whereby pressure fluid may be drained through said second conduit from said motor and means including the piston of said motor for regulating the drainage of operating fluid through said second conduit so as to preclude the 10 complete closure of said valve.

6. A valve testing arrangement comprising a valve, a fluid pressure operated motor connected to said valve for normally maintaining said valve in the opened position, a source of operating 15 pressure fluid, conduit means including a control valve for conducting operating fluid from said source to said motor, a second conduit having an inlet port in said motor and an outlet port in said control valve, means for operating said 20 control valve to uncover said outlet port to allow drainage of operating fluid from said motor, and means including a portion of said motor for closing said inlet port upon a movement of said motor to a position corresponding to a partly 25 closed position of said valve.

REED J. CAUGHEY.
